UNITED STATES PATENT OFFICE.

KARL E. AHLBERG AND JOSEPH AHLBERG, OF CHICAGO, ILLINOIS.

LOCK-CONTROLLED NUT AND SET-SCREW GUARD.

No. 870,533.

Specification of Letters Patent.

Patented Nov. 12, 1907.

Application filed February 23, 1907. Serial No. 359,013.

To all whom it may concern:

Be it known that we, KARL E. AHLBERG and JOSEPH AHLBERG, citizens of the United States, residing at Chicago, in the county of Cook and State of Illinois, 5 have invented certain new and useful Improvements in Lock-Controlled Nut and Set-Screw Guards, of which the following is a specification.

This invention relates to guards for the heads or nuts of bolts, the heads of set-screws, and similar 10 devices, and the object of the invention is to provide a simple, inexpensive, and efficient device to serve as a guard for set-screws, bolts, and similar fastening devices whereby articles of more or less value are often secured or supported in places or positions 15 where they are liable to be abstracted or stolen. For instance, automobile and bicycle lamps, which frequently represent considerable value, are commonly mounted on a vertical bracket and secured against accidental displacement by an ordinary headed set- 20 screw tapped through the sleeve on the shank of the lantern which engages the post of the bracket. Where the lantern is thus mounted, it is an easy matter for a person so inclined to loosen the set-screw and remove and make off with the lantern. Many other 25 articles of more or less value are similarly mounted and secured, making their unlawful abstraction an easy matter on the part of dishonest persons.

Our present invention affords a lock-controlled 30 guard or shield for the set-screw or similar fastening device which renders it impossible to loosen such set-screw or other fastening device without first removing the shield or guard, and this latter can be done only by the owner or other authorized person provided with a means for removing the same.

Briefly described, the invention may be said to consist in the combination with a fastening device having a squared head or nut forming a wrench-hold and one element of a locking means, of a guard in the nature 40 or nut and provided with the other element of a lock, said casing being rotatable relatively to said head or nut, so that the fastening device cannot be unscrewed by merely rotating the guard.

Our invention will be readily understood when considered in connection with the accompanying drawings showing a preferred embodiment thereof, in which,—

Figure 1 is a vertical sectional view through our improved guard, the same being shown as applied to 50 a set-screw for fastening a lantern shank to its supporting bracket; Fig. 2 is a detail elevation of the set-screw shown in Fig. 1, detached; Fig. 3 is an end view of the open end of the shield or guard, more particularly illustrating the locking tongues carried 55 thereby; and Fig. 4 is a perspective view of the guard, more particularly showing the pivoted mem-

ber carrying the movable locking tongue and a portion of the lock whereby said movable locking tongue is secured in operative position.

Referring to the drawings, 5 may indicate an ordinary lantern bracket such as is commonly secured to the dash, or other part of a vehicle, and 6 designates the vertical post constituting the upward extension of said bracket, over which fits the usual vertical sleeve 7, constituting the end member of the shank 8 of the 65 lantern or other article supported by the bracket.

9 designates the threaded stem of a set-screw, which screws into a threaded hole in one side of the sleeve 7 and is adapted to impinge tightly against the post 6 to prevent accidental displacement of the sleeve 7, 70 in a manner well understood. The head of the set-screw has the usual squared portion 10 for the application of a wrench to tighten and loosen the set-screw, as usual, and in rear of the squared portion it is provided with an annular groove 11 that constitutes one 75 element of the means for locking the shield or guard upon the head of the set-screw.

12 designates a cup-shaped casing having a round bore, the open end of which casing is adapted to fit over the head of the set-screw, as clearly shown in Fig. 80 1. The inner wall of the casing is provided on its lower side with an arc-shaped stationary locking tongue 13, that engages the groove 11 of the head. The upper portion of the casing has a longitudinal slot formed between parallel longitudinal ribs 12^a thereon; and 85 pivoted in this slot substantially coincident with the inner or open edge of the casing is a locking bar 14, which bar has formed integral therewith on its under side a short arc-shaped tongue 15 that also, when the bar is in closed position, enters the upper side of the 90 groove 11 of the head and co-operates with the fixed tongue 13 in locking the casing upon the head. To secure the bar 14 in closed position, it is provided at its free end with a depending hook 16 that constitutes one element of a spring lock mechanism mounted in 95 the closed end of the casing, which spring lock mechanism may be of any of the known forms or types controlled by a key inserted through the key-hole indicated at 17.

From the foregoing it will be apparent that when 100 the bar 14 is located in its closed position, the locking tongues 13 and 15 are so engaged with the locking groove 11 of the head that the guard or casing cannot be removed from the head, although said casing can be freely rotated on the head in either direction without effecting any turning movement of the latter. Hence the set-screw cannot be loosened by any amount of turning of the guard when the latter is locked on the head. To remove the guard, a key is inserted in the key-hole 17, and turned sufficiently to release the 110 hook 16, whereupon the arm 14 springs upwardly, or may be raised, according to the character of the spring

lock controlled by the key; and the raising of said arm retracts the locking tongue 15 from the groove 11 and enables the guard to be readily withdrawn.

From the foregoing it will be apparent that the device of our invention provides a safety device against tampering with the set-screw by unauthorized persons, in that, when applied, it prevents the application of a wrench or other loosening tool, and, being itself rotatable upon and relatively to the set-screw, 10 prevents the possibility of loosening the latter through turning of the guard. The device is cheaply made and quickly applied and removed; and requires no alteration or special construction of the screw-head or nut other than to provide therein a simple annular 15 locking groove. While we have shown the device as applied to the head of a set-screw, it will, of course, be understood that it is equally applicable to the same advantage to the nut or head of a bolt, or any other fastening device that is loosened or tightened through 20 the application of a wrench to a squared portion or head thereof.

We claim:

1. In a guard of the character described, the combination with a fastening device having a wrench-hold and a locking member, of a guard incasing said wrench-hold and provided with a movable key-controlled coöperating locking member, said coöperating locking members preventing re- 25

moval but permitting rotation of said guard upon said fastening device, substantially as described.

2. In a guard of the character described, the combination with a fastening device having a wrench-hold and an annular locking groove, of a guard incasing said wrench-hold and provided with a removable key-controlled locking tongue adapted to engage said locking groove in a manner to prevent removal but permit rotation of said guard upon said fastening device, substantially as described. 30 35

3. In a guard of the character described, the combination with a set-screw having a squared head provided with an annular groove, of a guard incasing said head, said guard having a key-controlled pivoted member carrying a locking tongue adapted to engage said annular groove in a manner to prevent withdrawal but permit rotation of said guard upon said head, substantially as described. 40

4. In a guard of the character described, the combination with a set-screw having a squared head provided with an annular groove, of a guard incasing said head, said guard having a fixed inwardly projecting locking tongue engaging said groove and further having a key-controlled pivoted member carrying a locking tongue adapted to engage said annular groove at a point opposite said fixed locking tongue, whereby said guard may be locked rotatably upon said head, substantially as described. 45 50
